UNITED STATES PATENT OFFICE.

JOSEPH MILLER, OF CLEVELAND, OHIO, ASSIGNOR TO THE CHAMPION REGISTER COMPANY, OF CLEVELAND, OHIO, A CORPORATION OF OHIO.

INDEX.

1,173,600.

Specification of Letters Patent. Patented Feb. 29, 1916.

Application filed April 3, 1912. Serial No. 688,293.

To all whom it may concern:

Be it known that I, JOSEPH MILLER, a citizen of the United States, residing at Cleveland, in the county of Cuyahoga and 5 State of Ohio, have invented a new and useful Improvement in Indexes, of which the following is a specification.

This invention relates generally to an index, and more particularly to an index to be 10 used in connection with a cabinet within which is contained an account system.

The object of the invention is to provide a simple and efficient means for holding the name bearing cards or slips, and a still 15 further object is to provide a card holding means of such character that the said cards or slips can be quickly and easily inserted or removed, and when inserted will be maintained in their proper positions and 20 held against dislocation.

Another object is to provide a transparent covering for said index thereby maintaining the same clean at all times.

With these objects in view, and also with 25 certain other objects as will hereinafter appear, my invention consists in the novel features of construction and combination all of which will be fully described hereinafter and pointed out in the claim.

30 In the drawings forming a part of this specification: Figure 1 is a perspective view of a cabinet provided with my improved index. Fig. 2 is a detail perspective view showing the rear side of the metal sheet or 35 plate which forms a part of my index. Fig. 3 is a detail perspective view showing a portion of one of the spacing and retaining strips. Fig. 4 is a detail perspective view of one of the name cards or slips. Fig. 5 40 is a face view of the index. Fig. 6 is a side or edge view of the same. Fig. 7 is a vertical sectional view on the line 7—7 of Fig. 5, and Fig. 8 is a horizontal section on the line 8—8 of Fig. 5.

45 In the practical embodiment of my invention I employ a thin metallic sheet or plate A, which has a series of slots A' punched therein, said slots being arranged in definite order, that is they are arranged 50 in parallel series with narrow intervening spaces. The portion of metal punched from the face of the plate to provide the slot A' is not detached but is pressed rearwardly at a right angle to the face of the plate providing a horizontal rest or stop A², said 55 rest or stop A² serving as a rest or support for the central portion B² of the name card or slip B, the body portion of said card being passed through the slot next above the rest or support upon which it is to rest 60 and the upper portion of the card will then be displayed above the slot, and in order to maintain these cards or slips in a flat position and also prevent their accidental dislocation I employ spacing strips C, which 65 are attached to the front face of the slotted plate intermediate the rows of slots as shown, it being understood of course that the slotted plate A is fastened to a suitable back or support D, which in the present instance is shown as the top or cover of the cabinet for containing the account system, but it will of course be understood that this index can be attached to any other suitable back or support. The spacing strips C are 70 75 preferably of thin metal channelled as shown at C', and flanged as shown at C², the panel shape of the strips maintaining the flanges at a sufficient distance from the face of the slotted plate to permit the ready 80 insertion and removal of the ends of the cards beneath the said flanges as shown in dotted lines in Fig. 5.

In order to protect the index against dirt and the like I provide a transparent covering panel E, preferably of glass mounted in a suitable metallic frame F hinged at the lower corners F' and adapted to engage 85 spring catches F² at the upper corners.

In operation spring catches F² are pushed 90 out, the transparent covering released and turned down to a horizontal position. Any card can then be removed by catching hold of the central portion thereof and pulling upwardly thereon, and a card can be inserted 95 whenever desired by introducing the central portion through the proper slot, inserting the ends beneath the flanges of the facing strip and forcing the same downwardly until the lower end of the central portion of 100 the card contacts with the horizontal rest or support upon the rear face of the slotted sheet or plate just below the slot through which the card is introduced, and as each slot has a corresponding rest or support it 105 will be understood that each and every name card or slip introduced will be held against vertical movement by resting upon the slot and will be held against lateral movement by having its ends beneath the flanges of the 110

spacing strips which not only serve as strips for separating the rows of slots but also serve as retaining means for holding the name cards in place.

5 Any system of arranging the cards may be employed, that is they may be arranged alphabetically or numerically or by a combined system of both.

What I claim is:

- 10 An index comprising a slotted plate or sheet the slots of said plate being arranged

Copies of this patent may be obtained for five cents each, by addressing the "Commissioner of Patents,

Washington, D. C."

in definite rows, the portion of the plate or sheet punched therefrom to form each slot being projected rearwardly, thereby providing a rest or support for a card or slip projected into the next slot above, and flanged strips attached to the face of the plate or sheet at the ends of the slots.

15 JOSEPH MILLER.
